DESIGN FOR A GAME BOARD

Fred Graef, Cincinnati, Ohio

Application February 7, 1939, Serial No. 82,844

Term of patent 7 years

To all whom it may concern:

Be it known that I, Fred Graef, a citizen of the United States of America and a resident of Cincinnati, in the county of Hamilton and State of Ohio, have invented a new, original, and ornamental Design for a Game Board, of which the following is a specification, reference being made to the accompanying drawing, forming a part thereof.

The article is of no appreciable or substantial thickness and the game features are flush with the surface.

The figure is a plan view of a game board showing my new design.

I claim:

The ornamental design for a game board, as shown and described.

FRED GRAEF.
